[57] **CLAIM**

The ornamental design for a housing for electric motor,
as shown and described.

DESCRIPTION

FIG. 1 is a plan view of a housing for electric motor
which embodies my new and ornamental design,
FIG. 2 is a side elevational view of the housing for
electric motor shown in FIG. 1,
FIG. 3 is an elevational view of the right-hand end of
the housing for electric motor shown in FIG. 1,
FIG. 4 is a perspective view, taken from above and
from the right-hand end, of the housing for electric
motor shown in FIG. 1,
FIG. 5 is a perspective view, taken from below and
from the right-hand end, of the housing for electric
motor shown in FIG. 1, and
FIG. 6 is a perspective view of the left-hand end of the
housing for electric motor, as that housing is viewed in
FIG. 1.

FIG. 1.

FIG. 2.

FIG. 3.

FIG. 6.
